US0D1067174S

(12) **United States Design Patent** (10) **Patent No.:** **US D1,067,174 S**
(45) **Date of Patent:** **** Mar. 18, 2025**

(54) **BATTERY**

(71) Applicant: **Honeywell International Inc.**,
Charlotte, NC (US)

(72) Inventors: **Garaga Phani Kumar**, Hyderabad
(IN); **Julius Jancarik**, Drasov (CZ);
Zoltan Alexi, Brno (CZ)

(73) Assignee: **HONEYWELL INTERNATIONAL
INC.**, Charlotte, NC (US)

(**) Term: **15 Years**

(21) Appl. No.: **29/817,255**

(22) Filed: **Nov. 30, 2021**

Related U.S. Application Data

(63) Continuation of application No. 29/736,997, filed on
Jun. 4, 2020, now Pat. No. Des. 940,650.

(74) *Attorney, Agent, or Firm* — ALSTON & BIRD LLP

(57) **CLAIM**

The ornamental design for a battery as shown and described.

DESCRIPTION

FIG. 1 is a perspective view of a battery in accordance with
the new design;

FIG. 2 is a first side elevation view thereof;

FIG. 3 is a second side elevation view thereof;

FIG. 4 is a front elevation view thereof;

FIG. 5 is a rear elevation view thereof;

FIG. 6 is a bottom plan view thereof;

FIG. 7 is a top plan view thereof;

FIG. 8 is a bottom, front perspective view thereof;

FIG. 9 is a bottom, side perspective view thereof; and,

FIG. 10 is a top, rear perspective view thereof.

1 Claim, 8 Drawing Sheets
